UNITED STATES PATENT OFFICE.

OSSIAN T. WAITE, OF OSHKOSH, WISCONSIN, ASSIGNOR TO THE WAITE GRASS CARPET COMPANY, OF OSHKOSH, WISCONSIN, A CORPORATION OF WISCONSIN.

DESIGN FOR A GRASS RUG OR CARPET.

47,550.

Specification for Design.

Patented July 6, 1915.

Application filed April 17, 1915. Serial No. 22,184. Term of patent 3½ years.

To all whom it may concern:

Be it known that I, OSSIAN T. WAITE, a citizen of the United States, residing at Oshkosh, in the county of Winnebago and State of Wisconsin, have invented a new, original, and ornamental Design for Grass Rugs or Carpets, of which the following is a specification, reference being had to the accompanying drawing, forming part thereof.

The figure in the drawing represents a plan view of the grass rug or carpet showing the design of the present invention.

I claim:

The ornamental design for a grass rug or carpet, substantially as shown.

OSSIAN T. WAITE.
